BOBBIN STRIPPING MACHINE

Filed April 25, 1927

2 Sheets-Sheet 2

Fig. 2.

Inventor:

Edgar A. Terrell
by Chas. F. Randall
atty.

UNITED STATES PATENT OFFICE.

EDGAR A. TERRELL, OF CHARLOTTE, NORTH CAROLINA.

BOBBIN-STRIPPING MACHINE.

Application filed April 25, 1927. Serial No. 186,227.

The invention is designed for application in connection with machines for stripping from bobbins and the like the so-called "waste" consisting of the residue of roving, 5 yarn, or the like, remaining upon a bobbin or other like carrier after the supply which was wound thereon has become exhausted as near to the end as is practicable in the regular operation of spinning mechanism, &c.

10 The invention consists, primarily, in the combination, in a machine for stripping bobbins and the like, with means for removing rovings, yarns, and the like, with the twist substantially intact from bobbins or other 15 carriers, of means for reworking the still-twisted strippings concurrently with such removal of the latter; secondly, in the combination with bobbin-stripping means of novel means for reworking the strippings.

20 In the case of some stripping machines the rovings or yarns as removed from the bobbins or other carriers are permitted or guided to pass from the stripper-element or elements to the floor below the machine, or to a convenient receiver. Other stripping machines are provided with means for conveying such rovings or yarns to a convenient place of deposit or receiver located elsewhere. In all 25 these cases the strippings are received and accumulated in the form of lengths of more or less intact and still-twisted rovings or 30 yarns. For the purpose of being reworked, when reworking is desired, the still-twisted rovings or yarns are taken in bulk from the 35 said accumulation and carried to a reworking machine, which latter is a second machine, employed for reworking purposes. This procedure involves the transferring of the loose rovings or yarns in bulk from the 40 place of accumulation to the reworking machine, and the performance of the reworking as a separate operation. By "reworking" 45 is meant the treatment by which the fibers of the rovings, yarns, etc., are torn apart so as to resolve the rovings, yarns, or the like, from their more or less twisted condition into a more or less fleecy state.

The general object of the present invention is to provide for reworking the rovings, 50 yarns, etc., as fast as they are stripped from bobbins or other carriers, so that in one unbroken sequence the waste is stripped from the bobbins or other carriers thereof and almost immediately reworked, without manual 55 handling, and the material is discharged in reworked condition.

An illustrative embodiment of the invention is shown in the accompanying drawings, in which latter,—

Fig. 1 is a view of a machine comprising 60 the said embodiment, partly in elevation and partly in vertical section, only a part of the bobbin-stripping portion of the organization being represented

Fig. 2 is a view looking in the same direction as in Fig. 1, but with parts in section on line 2, 2, of Fig. 3.

Fig. 3 is a view of the machine taken from the left-hand side in Fig. 1, with certain parts in section on line 3, 3, of Fig. 1.

Having reference to the drawings,—

The latter show bobbin-stripping means organized to unwind residues of rovings, 70 yarn, or the like from bobbins or the like carriers, and to deliver the substantially intact 75 rovings or the like, as unwound, into a receptacle from which the material is delivered to the fiber-working elements of the reworking means. In this instance the said bobbin-stripping means embodies the principles of 80 the machine of the United States patent to Richard Walworth, No. 1,080,794, granted December 9, 1913 for improvement in bobbin 85 stripping machines. As illustrated, it comprises two main stripping rollers 1, 1, (shown somewhat diagrammatically) instead of the single main roller shown at *a* in the said patent. At 2, 2, Fig. 3, are shown auxiliary 90 rollers (also shown somewhat diagrammatically) cooperating, respectively, with the respective main rollers; that is to say, there is an auxiliary roller 2 cooperatively associated with one of the main rollers 1, and a similar auxiliary roller cooperatively associated with the other main roller. These auxiliary rollers 95 2, 2, perform the same bobbin-retaining and guiding functions that are performed by the auxiliary roller *b* and guide-bar *d* of the patent aforesaid, while in addition they respectively cooperate with the main rollers 100 with which they are associated in performing the function of drawing from the bobbins or the like the residues of roving thereon, as in the case of the auxiliary roller *b* of the patent. Rotation of the individual bobbins as a 105 result of contact with the surfaces of the rotating rollers 1 and 2, accompanied by end-wise travel of the bobbins lengthwise of the rollers 1, 1, 2, 2, take place in the case of the machine illustrated herein, just as in the case 110 of the machine shown and described in the patent, through the utilization of the same

principles. At 3, 3, Fig. 1, are brushes which make contact with the surfaces of the rollers 1, 1, 2, 2, and serve to remove from such surfaces rovings clinging thereto.

Below the group of rolls 1, 1, 2, 2, I provide a hopper (indicated somewhat diagrammatically) formed by inclined sides 4, 4, converging downwardly, and at the bottom of the hopper I locate the upper run of an endless card-clothed conveyor-apron 5, Figs. 1 and 2; extending lengthwise of the rollers and extending some distance beyond their ends at one end of the machine, where it passes around a supporting-roll 6, Fig. 2. The said upper run receives the rovings as they fall from the rollers 1, 1, 2, 2, and conveys them to the said end of the machine. At such end of the machine I provide a card-clothed reworking roll 7, Fig. 2, the teeth of which engage with the rovings carried by the conveyor-apron, also, a second card-clothed reworking roll 8, the teeth of which take from those of roll 7 the partially reworked rovings. The casing 9 enclosing the said apron-supporting roll 6 and reworking card-clothed rolls 7 and 8 encloses also a fan 10, Figs. 2 and 3, mounted upon the shaft 11 of card-clothed roll 8; while from an outlet 12 in connection with the fan-chamber 13 a conduit 14 Figs. 1 and 2, leads to any desired discharging point. The front wall, 15, Figs. 1 and 3, of the casing is, or may be, formed with openings 16, 16, inwardly through which air may flow as drawn in by the fan.

The driving arrangement shown in the drawings comprises a round belt 17 passing partly around a grooved pulley 18, Fig. 3, on the shaft of one of the stripper-rolls 1, and then around a like pulley 19 on the shaft of the other roll 1, a guide-pulley 20, and pulleys 21, 22, 23, on the shafts of card-clothed rolls 7 and 8 and of the supporting-roll 6 of the conveyor-apron. The rolls are or may be driven so that rolls 1, 1, will make 360 R. P. M., and that the supporting roll 6 will revolve at 440 R. P. M., the card-clothed roll 7 at 660 R. P. M., and card-clothed roll 8 at 1000 R. P. M.

In the operation of the illustrated organization, the rovings unwound by the action of rolls 1, 1, 2, 2, drop from the latter to the bottom of the hopper, where they are received upon the upper rim of the conveyor-apron 5. By the movement of the latter the substantially intact rovings are carried to card-clothed roll 7, the teeth of which, preferably doffer fillet, removes the rovings from the apron, and at the same time the said teeth tear the rovings apart to a greater or less extent by reason of the fact that roll 7 has a higher surface speed than the conveyor-apron. The teeth of the card-clothed roll 7

carry the partially reworked rovings around to a point where such material comes within the range of action of the teeth, preferably straight burnisher fillet, of the card-clothed roll 8. As roll 8 rotates at a higher surface speed than roll 7, the rovings are still further disintegrated. As fast as the said teeth of roll 8 removes the material from the teeth of roll 7, the material flies off from the teeth of roll 8 into the enclosed space surrounding roll 8. The material thus thrown into the said space is carried away by the air-motion due to the suction of the fan and is blown by the fan through the outlet 11 and conduit 13 to the desired point.

What is claimed as the invention is:—

1. In a machine for stripping bobbins and the like, the combination with means for removing rovings, yarns, and the like, from bobbins or other carriers, of a toothed conveyor-apron receiving the stripings from such means, and a toothed roll cooperating with said toothed conveyor-apron to rework the stripings. 80

2. In a machine for stripping bobbins and the like, the combination with means for removing rovings, yarns, and the like, from bobbins or other carriers, of a toothed conveyor-apron receiving the stripings from such means, and toothed rolls cooperating with said toothed conveyor-apron and with each other in reworking the stripings and delivering the latter in a reworked state. 90

3. In a machine for stripping bobbins and the like, the combination with means for unwinding waste residues from bobbins or other carriers, of a conveyor-apron receiving the stripings from such means, and toothed rolls to which the stripings are fed by the said conveyor-apron and by which the stripings are reworked. 100

4. In a machine for stripping bobbins and the like, the combination with means for unwinding waste residues from bobbins or other carriers, of a toothed conveyor-apron receiving the stripings from such means, and toothed rolls cooperating with said toothed conveyor-apron and with each other in reworking the stripings and delivering the latter in a reworked state. 105

5. In a machine for stripping bobbins and the like, the combination with means operating to remove rovings, yarns, and the like, from bobbins or other carriers with the twist substantially intact, of a toothed surface receiving the still-twisted stripings as they pass from the said removing means, and other toothed surfaces by which the material supplied by the toothed surface first mentioned is reworked. 115
